STITCH INDICATOR PLATE FOR SEWING MACHINES

Frederick H. Leigh, New York, N.Y., assignor to The Singer Manufacturing Company, Elizabeth, N.J., a corporation of New Jersey

Application April 5, 1957, Serial No. 45,599

Term of patent 14 years

(Cl. D70—2)

Fig.1.

Fig.2.

Fig. 1 is a perspective view of the stitch indicator plate of my design as it appears when applied to a sewing machine; the dotted indication of the sewing machine being for illustrative purposes only.

Fig. 2 is a perspective view of the stitch indicator plate per se.

I claim:

The ornamental design for a stitch indicator plate for sewing machines, as shown and described.
